Specification of Letters Patent.

Patented Jan. 6, 1914.

Application filed November 14, 1910. Serial No. 592,363.

To all whom it may concern:

Be it known that I, HARRY B. SHREVE, a citizen of the United States of America, and a resident of Chicago, county of Cook, State of Illinois, have invented certain new and useful Improvements in Electric Hoists, of which the following is a specification.

This invention relates to hoisting apparatus and has for its main objects an improved construction of the housing, an improved arrangement of the operating mechanism within the housing, and an improved housing of the electrical connections leading to the operating mechanism.

15 A specific construction illustrating this invention is shown in the accompanying drawings, in which:

Figure 1 is a perspective view showing the outside appearance of a specific form of electric hoist constructed according to this invention. Fig. 2 is a right-hand end elevation of the same. Fig. 3 is a transverse section through the winch drum and its casing, taken on the irregular line A—A of Fig. 4.

25 Fig. 4 is a side elevation, partly sectional, the parts which are shown in section being represented as if cut along a vertical plane extending longitudinally through the middle of the apparatus. Figs. 5 and 6 are details showing the arrangement of the brushes and collector rings by means of which connection is made with the line conductors, the plane of projection on which the parts are represented corresponding to the line B—B of Fig. 4. Figs. 7, 8, 9, and 10, are sections taken on the lines C—C, D—D, E—E, and F—F, respectively, of Fig. 4. Figs. 11 and 12 are sections of the mechanical brake mechanism, taken on the lines 30 G—G, and H—H, of Fig. 9.

In the construction shown in the drawings, the mechanism is subdivided into six units or groups of parts, and the casing is subdivided into sections separable in such manner that each of said groups of parts may be readily accessible without disturbing any of the other groups.

The casing section 1 contains the controller or rheostat for controlling the speed and direction of rotation of the electric motor; section 2 is divided into two parts by a transverse partition, and these parts respectively contain the mechanical brake mechanism and the gear train; the middle section 3 of the casing contains the hoisting drum;

section 4 contains the motor; and section 5 incloses the electrical brake.

The casing is easily separable at any of the joints between the successive sections, and the connections between the mechanisms in the successive sections are such that each may be removed and repaired or assembled independently of the contents of the other sections.

All of the casing joints are circular and of the type which is called "right angled dovetail", which, besides insuring accurate axial alignment of the casing sections when they are fastened together, also prevents the passage of water, oil and dust into or out of the casing.

The controller which is housed within section 1 of the casing will not be herein described in detail, as its specific construction does not form a part of the present invention, and may be of any suitable form, dependent upon the type of electric motor which it controls. As is indicated by the controlling mechanism shown in the drawings, the form of controller which has been used in connection with the herein described apparatus, is one in which the speed changes and reversal of the motor are controlled by rocking a lever 6 by means of pull cords 7 and 8. On the outside of the casing, there is an automatic cut-out mechanism which shifts the lever 6 so as to cut off the current from the motor, and stop the motor when the load carrying hook 9 reaches a predetermined limit of upward movement. This cut-out mechanism comprises a crank or lever 10 connected by a link 11 with the lever 6, and having a shoe 12 located to engage the hoisting sheave 13, from which the hook 9 is suspended. These parts are so arranged that when the sheave 13 engages the shoe 12, it will cause the lever 10 to swing the lever 6 to its "off" position. There is also provided a spring 6^a which coacts with a pair of levers 6^b, an arm 6^c and a stop 6^d, to return the controller lever to its off position, as soon as it is released by the operator.

The support for the casing may be of any suitable form, but it is preferred to attach the support to the middle section 3, so that the other sections may be easily removed with their contents without disconnecting the casing as a whole from the support. In the form shown, the support consists of a hook or eye 14. This hook has swiveled

connection with the middle section 3 of the casing, and the weight of the casing is transmitted to the hook through a ball bearing 15, which allows the casing to be readily turned about the shank of the hook. The line conductors 16 for the electrical energy enter the casing near the hook 14, and are connected to individual slip rings 17, which are respectively engaged by contact brushes 18.

In the form shown, the slip rings 17 are carried by a stationary cap 19 secured to the hook 14, and the brushes are carried by a circular boss 20 at the top of the casing section 3. The conductors are led from the brushes 18 outward through an aperture in the side of the boss 20, with which there is connected a pipe 21, connected by a T with the pipe 22, connecting the casing sections 1 and 4. The current distributing wiring is therefore on the outside of the casing proper, and is readily accessible for connection or disconnection at times when the casing sections are to be separated. For this purpose, connections are made at the respective boxes 23 with the controller and motor, in such manner as to be readily accessible through the covers of said boxes.

The motor is housed within the casing section 4, and is represented in the drawings by said casing section, and such other parts as are visible in Fig. 4. The end of the rotor shaft 24, which is toward the right in Fig. 4, has an axial socket, preferably of hexagonal or other flat sided form, for receiving the correspondingly formed end of the floating shaft 25. The righthand end of the shaft 25 is journaled in a bearing in the partition 26, which forms a removable end plate for the righthand end of the casing section 2. The periphery of the plate 26 is circular, and closely fits a circular seat in the end of the casing 2, which insures perfect alinement of the bearing when the casing 2 and its plate 26 are in position in the machine. The periphery of the plate 26 also fits within the casing section 1 of the controller, and insures the alinement of the sections 1 and 2. The shaft 25 is also supported at other points by suitable bearings in the partition walls 27, 28 and 29 of the casing.

The winch drum 30 is splined to a hollow shaft or quill 31, which is concentric with the shaft 25, and the bearing for the quill 31 in the partition 28 is made in the form of a removable central plate or bushing 32. When the casing sections 2 and 3 are separated, the shaft 25 will be withdrawn with the section 2, as will hereinafter appear, but the quill 31 will remain in the section 3, being prevented from being withdrawn with the shaft 25 by the spline 33. The quill 31 may, however, be withdrawn through the partition 28 by first removing the bushing

32. This allows of inserting and withdrawing the drum 30 through the opening 34 at the bottom of the drum casing 3, and allows the partitions 28 and 29 to be made integral with the other parts of the casing section 3.

The connection between the shaft 25 and the drum 30 comprises a gear train and the mechanical brake mechanism which are housed within the respective compartments of the casing section 2. As the casing section 2 is oil tight, a quantity of oil may be retained in the bottom of the gear casing, so that the lower gears dip below the surface. The operation of the gears will then insure that all parts of the gearing are properly oiled. In order to regulate the amount of oil, the casing section 2 has an oil hole 35, Fig. 7, which is so located as to overflow after the oil has reached the desired level. This oil hole is closed by a cap 36. By preference, the gear train is made up of a series of alternate pinions 37 and gears 38, the pinions being all of equal size, and the gears being also all equal in size. The first of the pinions 37 is fixed on a quill 39, which is concentric with the shaft 25, and the last of the gears 38 is fixed on the quill 31. There are two separate trains of intermediate gears connecting said first pinion 37 and last gear 38, and as half of the load is thus taken by each gear train, the strain on each individual gear tooth is reduced to one-half of what it would be in the case of a single gear train, thus reducing the liability of breakage of the gears and making it possible to reduce the size of the gears for any given load.

The mechanical brake comprises a pair of friction disks 40 and 41, concentrically mounted with respect to the shaft 25, but in axial alinement with each other. The disk 40 is keyed to the quill 39, and the disk 41 is supported by, but loose, on the shaft 25. Relative rotation of the disks 40 and 41 is prevented by means of the pins 42, which are rigidly secured in one of said disks and axially slidabie in the other. The two disks are urged apart by means of helical springs 43 surrounding the pins 42. These disks together constitute an expandible clutch member, which, through its expansion and contraction, may be forced into or withdrawn from driving engagement with the clutch member 44, with which it cooperates. The clutch member 44 consists of two disks located for frictional engagement with the adjacent faces of the disks 40 and 41 respectively, and rigidly connected together. The member 44 is journaled to rotate concentrically of the shaft 25, but is driven only through its frictional connection with the disks 40 and 41. The member 44 has an annular flange 45 located to coact with friction ratchet pawls or toggles 46, which are mounted on the partition 27 of the casing

section 2 and arranged to automatically lock the member 44 against rotation in one direction, while permitting its free rotation in the other direction, as will be seen from Fig. 8. 5 The pawls 46 carry at their outer ends friction shoes 47, which are faced with leather or other suitable material for frictional engagement with the inner periphery of the flange 45. The pawls 46 are held in position by pivot studs 48, but the boss 49 is provided with bearing surfaces 50 which fit the hubs of the pawls 46, and assist the studs 48 in withstanding the thrust of the pawls. The friction shoes 47 are normally urged into contact with the flange 45 by means of springs 51.

From Fig. 8 it will be seen that the member 44 will be free to rotate in the direction of the arrow 52, as the frictional contact between the shoes 47 and the flange 45 swings the pawls 46 toward a position for reducing the pressure of the shoe against the flange. Rotation of the member 44 in the opposite direction causes the pawls 46, by virtue of said friction contact, to swing toward a radial position, and thereby forces the shoes 47 outward and increases the frictional contact until the member 44 is effectually locked. 20

30 A pair of diametrically opposite sets of toggle links 53 is interposed between the disks 40 and 41, as may be best seen in Figs. 9, 11 and 12, for the purpose of drawing them out of engagement with the member 44.

35 Each set comprises a pair of links pivotally connected to the disks 40 and 41 respectively, and joined at their adjacent ends by means of arms or studs 54 carried by a hub 55, which is fast on the shaft 25. The studs 54 have ball shaped enlargements fitting the apertures in the adjacent ends of the toggle links 53. This form of pivotal connection

40 between the links is provided on account of the necessary angular movement of the studs 54 in the apertures. The toggle links are so placed that when the shaft 25 is rotated in the normal direction for winding the hoisting cable on to the drum 30 for lifting a load, the toggles will force the disks 40 and

45 41 into driving engagement with the member 44. When, therefore, the shaft 25 is stationary, the pull of the load on the drum 30 will have the same effect of expanding the toggles and forcing the disks 40 and

50 41 into gripping engagement with the surfaces of the member 44, but as the member 44 is locked by the pawls 46 against reverse rotation, it automatically locks the load at any position through the mere stopping of

55 the motor. If, however, the motor is reversed, the pull of the shaft 25 on the toggles 53 pulls the disks 40 and 41 toward each other against the action of the springs 43, thus releasing the disks 40 and 41 from the brake member 44, and allowing the pull

of the load on the drum 30 to unwind the cable from said drum. The unwinding of the cable is, however, controlled by the speed of reverse rotation of the motor, since any tendency of the load to cause the disk 40 to rotate at a speed in excess of that of the shaft 25 will remove the pull on the toggles and allow the springs 43 to force the disks 40 and 41 into frictional engagement with the brake member 44. As the member 44 cannot rotate in such reverse direction, the unwinding of the hoisting cable 56 cannot take place except while the shaft 25 is turning so as to pull the disks 40 and 41 away from the member 44, as above described. 70

In the section 5 of the casing, there is housed an electric brake which comprises a brake member or wheel 57 fixed on the rotor shaft 24 of the motor, and a pair of brake shoes 58, which are urged by springs 59 into gripping engagement with the wheel 57. The brake shoes 58 are withdrawn from such frictional engagement by means of electromagnets 60, which are connected in the same circuit with the stator windings of the motor, so that whenever the motor windings are energized, the electric brake will be automatically released, but as soon as the electric current is cut off from the motor, the magnets release their armatures and the springs 59 will force the shoes 58 into engagement with the wheel 57 and stop the shaft 24, and, through it, the shaft 25. The electric brake supplements the mechanical brake, and gives additional holding power at times when the current is cut off, since it locks the shaft 25, and thereby causes the pull of the load on the cable to expand the toggles 53, and increase the frictional grip between the disks 40 and 41, and the member 44. 90

The operation of the device shown is as follows:—The controller is so arranged that when the operator pulls down on the cord 7, the windings of the motor will be energized, and the electric brake will be automatically released. The motor, acting through the shaft 25, the member 55, and toggle links 53, drives the disk 40, and through the connected trains of gears, rotates the drum 30 so as to hoist the cable 56. During this movement, the disks 40 and 41 are forced into gripping engagement with the clutch member 44, but the direction of rotation is such that the ratchet brake shoes 47 allow the member 44 to rotate freely. In case the motor is now stopped, the pull of the load on the hauling cable 56 would tend to drive the parts in the reverse direction, and this causes the ratchet brake shoes 47 to grip the member 44. As the disks 40 and 41 are normally urged by the springs 43 into gripping engagement with the clutch member 44, the locking of said 110

115

120

125

130

member 44 by the ratchet brake shoes therefore locks the drum. As the electric brake also secures the armature against rotation, any tendency of the disk 40 to slip relatively 5 of the member 44, would cause the toggle links 53 to be set up by the member 55, so as to force the disks 40 and 41 into still tighter engagement with the member 44. When the cord 7 is pulled down for starting 10 the motor, the shoe 12 of the automatic cut-out mechanism is lowered. If it should happen that the operator fails to stop the motor before the hook 9 had reached the extreme upper limit of its movement, the 15 sheave 13 will engage the shoe 12, and cause the crank 10 to reset the controlling lever 6 to its off position, and stop the motor. In order to cause the load to descend, it is necessary to reverse the motor, but the brake 20 mechanism is so designed that the motor need exert merely enough power to release the brake, thus allowing the load to descend by its own gravity. The reversing of the motor may be accomplished in any usual 25 way, and is preferably done by arranging the controller so that when the lever 6 is turned in the reverse direction beyond its off position, as by pulling the cord 8, the current supplied to the motor will be reversed in such manner as to cause reverse rotation. When the motor is reversed, the energizing of the windings thereof also energizes the magnets of the electric brake, and releases the rotor shaft 24. The load 30 cannot descend at a speed which exceeds the speed of reverse rotation of the shaft 25, as such excess speed would set the mechanical brake and cause the load to be locked to the frame until the rotation of the shaft 25 35 again releases it, as has been explained. The mechanical brake thus acts to automatically lock the load in any position, and permit it

to descend only at a speed corresponding to the speed of the shaft 25 when driven in a reverse direction.

Although but one specific embodiment of this invention is herein shown and described, it will be understood that numerous details of the construction shown may be altered or omitted without departing from the spirit 45 of this invention, as defined by the following claim.

I claim:—

In a hoist, the combination of a casing, a winch drum journaled in said casing, a motor mounted in said casing at one side of said drum, operating mechanism mechanically interposed between said motor and drum, a controller mounted in said casing at the side of said drum which is distant 55 from the motor, said casing comprising a central section within which said drum is mounted, and individually removable sections respectively carrying said motor, operating mechanism and controller, means connected to the section of the casing containing the winch drum for supporting the casing, wiring entering said casing at said supporting means and connecting an outside source of electricity with said controller and 60 motor, and a housing for said wiring external to said casing and comprising individual closed terminal boxes for said motor and controller, and a conduit connecting said terminal boxes, said conduit and terminal 65 boxes being adapted to permit ready access from the exterior to said wiring.

Signed at Chicago this 10th day of November, 1910.
